US00D783655S

(12) **United States Design Patent** (10) **Patent No.:** **US D783,655 S**
Hu (45) **Date of Patent:** **** Apr. 11, 2017**

(54) **DISPLAY SCREEN WITH GRAPHIC USER INTERFACE**

(71) Applicant: **Jingtao Hu**, Guangdong (CN)

(72) Inventor: **Jingtao Hu**, Guangdong (CN)

(**) Term: **15 Years**

(21) Appl. No.: **29/543,088**

(22) Filed: **Oct. 21, 2015**

(30) **Foreign Application Priority Data**

Apr. 21, 2015 (CN) 2015 3 0107439

(51) **LOC (10) Cl.** **14-04**

(52) **U.S. Cl.**

USPC **D14/486**; D14/490

(58) **Field of Classification Search**

USPC D14/485-495

CPC G06F 3/0489; G06F 15/0225

(57) **CLAIM**

The ornamental design for a display screen with graphic user interface, as shown and described.

DESCRIPTION

FIG. 1 is a front view of a display screen with graphic user interface showing my new design; and,

FIG. 2 is a front view of a second embodiment thereof. The outermost broken line showing a display screen and all other broken lines showing portions of the graphical user interface form no part of the claimed design.

1 Claim, 1 Drawing Sheet
